UNITED STATES PATENT OFFICE.

JOHN C. BECKFIELD, OF PITTSBURG, PENNSYLVANIA.

PNEUMATIC-TOOL LUBRICATOR.

No. 909,740.

Specification of Letters Patent.

Patented Jan. 12, 1909.

Application filed March 26, 1903, Serial No. 149,633.

Renewed December 16, 1907. Serial No. 406,766.

To all whom it may concern:

Be it known that I, JOHN C. BECKFIELD, a citizen of the United States, residing at Pittsburgh, in the county of Allegheny and State of Pennsylvania, have invented a new and useful Improvement in Pneumatic-Tool Lubricators, of which improvement the following is a specification.

My invention relates to devices for oiling or lubricating pneumatic tools.

The object of my invention is to produce an oiler which is adapted to be arranged between a source of air supply and a pneumatically operated tool, or in the air circuit of a pneumatic tool, in such manner that a modicum of the lubricant is taken up and carried by the air to the operative parts of the tool. In one form of my device, air is to be passed into the lubricant reservoir and returned to the main supply pipe, in its return passage carrying to the operative parts of the tool a regulated quantity of lubricant. In another form of my device the lubricant is fed by capillary attraction to the air conducted at a point approximating the median line of volume of the vessel, and then carried by the air to the operative parts of the tool. To accomplish these objects my invention consists in the novel constructions and arrangements of parts hereinafter more specifically described, reference being had to the accompanying drawings, forming part hereof, in which—

Figure 1 indicates a central longitudinal section of my improved automatic oiler. Fig. 2 is a transverse section through the center thereof. Fig. 3 is an end view of the thimble. Fig. 4 is a plan view of a modified form of diaphragm, one section of the lubricant vessel being removed. Fig. 5 is a longitudinal section of the same. Fig. 6 is a section through the valve on line *x--x* of Fig. 5. Fig. 7 is an enlarged sectional detail of modified form of feeder. Fig. 8 is an elevation of oiler and pneumatic tool connected. Fig. 9 is a sectional view of modified form of reservoir.

Like reference characters indicate like parts wherever they occur.

Referring to said drawings, A is a pneumatic tool; B is a section of hose connecting the same with the automatic lubricator C, and D is a portion of the air supply pipe. It will be observed that the oiler is in the air circuit of the tool, and that the oil or other lubricant is charged therein to a point below the median line of the vessel so that in what-

ever position the tool may be placed, or the oiler relatively thereto, the oil or other lubricant is prevented from oozing or leaking into the air passage or tube but is conveyed or carried by the air to the working or operative parts of the tool A, in regulated quantities as hereafter specified. The said lubricator comprises a vessel or reservoir, of any suitable form, preferably formed in two sections, 1, 2, and arranged or disposed in the air circuit of the tool at a suitable distance therefrom. Section 1 is provided with an outwardly projecting threaded flange 3, which is adapted to be screwed into the annular threaded groove 4, formed in the outwardly projecting flange 5 of section 2. The edge of said flange 3, adjacent to the corresponding edge of flange 5, is provided with a recess 6 to receive the edges of the perforated plate 7, which divides the interior of the vessel.

Section 1 is provided with an inwardly projecting threaded tube 8, the opening in which is in alignment with the air supply opening 9, formed in the boss 10 projecting from the side of section 2. Immediately opposite said boss a similar boss 11 is formed on section 1, and section 2 is likewise provided with an inwardly projecting tube 12 provided with a passage 13 in alignment with both the air supply and discharge openings 9 and 14. The said sections when assembled constitute a single chamber, the opposite sides of which are provided with contracted bores or orifices for the attachment of the adjacent ends of air supply pipe D and pipe or conduit B, respectively, with said chamber, the tube 15, the ends of which are located in said contracted bores, constituting, in conjunction with said bores, the continuous pipe or conduit leading through said chamber. The inner ends of the tubes 8 and 12 are enlarged forming a shoulder in the passage, and a seat for the connecting, adjusting and regulating tube 15, which projects therein, said tube being adapted for regulation of the air supplied to the vessel C and the oil carried from the vessel to the air pipe, one end of said tube 15 being screw threaded and screwed into the threaded portion of tube 8. The said tube 15 is cylindrical in cross section; the threaded end and a portion of its regulating end are cut to leave spaces *a*, *b* and *c* between the outer wall of said tube 15 and the inner wall of the tube 8, in which said tube 15 projects; said tube

15 is made smaller in the inner diameter than the inner diameter of tubes 8 and 12 for the purpose hereinafter specified. The other end is cut to form taper passages for 5 the admission of air to the oil reservoir. 16 and 17 are thimbles mounted on the tubes 8 and 12 and are of slightly greater diameter than said tubes 8 and 12 so as to form a space d between the inner walls of said 10 thimbles and the outer surfaces of the tubes, for the purpose of better regulating the introduction of lubricant to the fluid motive passage, also of preventing the possible introduction of any organic substance to the 15 passages into the motive fluid or air passage. The inner ends of the thimbles are provided with inwardly projecting flanges which snugly fit upon the cylindrical part of tube 15 at the point where the tubes 8 and 20 12 approximately meet, and their outer ends with notches 18 and 19 to enable oil or other lubricant to enter the space d , between the outer surfaces of the tubes and the inner walls of the thimbles. Section 1 is provided 25 with a boss or projection 20 in which a socket 21 is formed, a passage 22 from said socket to the interior of the vessel being provided to charge or fill the same, and a similar passage 23 to exhaust the air from said 30 vessel. The socket is adapted to be closed by a plug, and the passages, particularly the oil charging passage, are arranged below and angularly disposed with relation to the median line of the vessel, when the same is 35 held in charging position, so as to prevent the filling of said vessel up to said median line.

In Figs. 4, 5, and 6 I show a modified form of my device, in which the vessel or reservoir is formed of two sections A' and B', which are secured together by screws or bolts. Each of said sections is provided with internally projecting tubes 8', 12', which are connected by an internally disposed thimble or tube 15'; the inner ends of said tubes 8' and 12', respectively, being enlarged to receive the ends of said tube 15' whereby a continuous passage is formed between the supply and discharge openings 40 9' and 14', respectively. An internal centrally disposed diaphragm 7', having a central opening or orifice, which surrounds the connecting tubes 15', divides the interior of the vessel into two compartments, and is 45 perforated so as to permit the contents of the vessel to more or less freely pass from one compartment to the other. The tubes 8' and 12', respectively, have loosely mounted thereon thimbles 16' and 17'. The supply opening of said vessel is controlled by 50 a two-way valve, 24, which contains a port to admit air through the continuous passage of the tubes or conduit, and also a port to replenish the vessel with oil or other lubricant. Normally the air port of said valve is

open and the port to replenish the vessel closed.

In Fig. 7 I show a modified form of the lubricant feeding apparatus, in which, between the loosely mounted thimbles 16'' and 17'', I insert the absorbent material, designated by the reference character 21', which covers the inwardly projecting air tubes 8'' and 12'' and said absorbent material feeds or conveys the oil or other lubricant to the 75 interior of the air passage in the manner similar to a wick.

In Fig. 9 I show a modified form of lubricant reservoir, which, instead of being spherical in form, is oblong or substantially 80 oblong, and is subdivided by interiorly disposed funnel shaped cups, 22', 22', the sides of which are perforated. This form of reservoir is formed in two sections A², B², and the interiorly disposed tubes 8'' and 12'', respectively, approximately coincide in 85 depth with either section, and when said sections are secured together form a continuous passage through the interior of the vessel. The supply opening is controlled by 90 a valve similar to that shown in Fig. 5, and the funnels subdividing the vessel interiorly are perforated so that more or less free communication is obtained between the different compartments. 95

The funnel shaped cups 22' 22' serve to feed the lubricant to the openings which are shown approximately on the median line of the vessel; and when the apparatus is shifted into any other position than that shown in 100 Fig. 9, the oil by gravity will be fed down the inclined cups 22', 22', to said opening, and as a matter of course the oil would shift correspondingly with the position in which the apparatus was held. The agitation of 105 the apparatus when in actual use also causes a small quantity of the lubricant to be fed or carried by the inclined cups, as shown in Fig. 9, to the median line of the vessel and from thence to the operative parts of 110 the pneumatic tool.

The operation of my device is as follows:—The reservoir or vessel being charged with any suitable lubricant, to a point below the median line of the vessel, and the oiler 115 being inserted or placed in the air circuit of a pneumatic tool or similar device, or between a source of supply of air and the tool to be lubricated as shown in Fig. 8, air is admitted to the air supply opening 9, assuming that the air is traveling in that direction, and passing through the passage 13 impinges against the shoulders formed at the junction of said passage 13 with the end of tube 15, and passing therearound enters the 120 space passages a' , enters the space between the thimble 17 and the tube 12, and thence through the notches 19 in said thimble 17 into the reservoir. On its return passage to 125 the motive fluid passage, the air enters the 130

space between the thimble 16 and the tube 8 through the notches 18 into the taper passages *a, b, c*, into the motive fluid passage, where it is taken up by the continuous flow 5 of air to the tool being lubricated, the air which entered the reservoir carrying with it on its exit passage a portion of the lubricant contained therein.

It may be observed that the tube 15 is of 10 smaller interior diameter than that of the inner diameter of the tubes 8 and 12 thus causing a more or less throttling action or slight interruption of the air at the entering end of tube 15 causing a portion of the air 15 to be directed into the oil compartment of the vessel, while the action of the air as it discharges from the tube at the exit end thereof is that of a siphon, causing a suction on the ports at that portion and consequently 20 drawing from the vessel the air previously forced into it by the pressure consequent on the throttling action at the entering end of tube 15.

It will be observed that the point of ingress and egress of the portion of air diverted into the reservoir is preferably located at the point coincident with the median or near the median line of the vessel, and coincident with the level of the lubricant that may be contained therein when the oiler is held in a position that would throw the motive fluid passages in a vertical plane. This is for the purpose of preventing oil escaping into the motive fluid passages when 35 the air is shut off and the vessel accidentally held in the position indicated.

I claim as my invention and desire to secure by Letters Patent:

1. An oiler comprising a vessel adapted to 40 contain lubricant having an uninterrupted centrally disposed passageway therethrough for the passage of air, ducts located at a point slightly above the maximum level of the lubricant when the passage is vertically disposed, communicating between the receiver and said motive fluid passage for the ingress of air to said reservoir and its egress therefrom, whereby the passage of air through said reservoir feeds a portion of the lubricant contained in said reservoir to the motive fluid passage, and means to prevent the discharge of lubricant from said reservoir except when carried therefrom by the passage 45 of air therethrough.

2. An oiler comprising a vessel adapted to 55 contain a lubricant and having an uninterrupted passage centrally disposed therethrough for the passage of motive fluid, means to by-pass or divert a portion of said fluid into the body portion of said vessel, and means to enable the return of said diverted motive fluid to said motive fluid passage, whereby a portion of the lubricant is 60 constantly carried by the diverted motive fluid into the said motive fluid passage and

from thence to the operative parts of a motor connected to said oiler.

3. An oiler comprising a vessel having a chamber adapted to contain a lubricant, a motive fluid conduit extending through the vessel and surrounded by the lubricant chamber, and means adapted to by-pass or divert a portion of the motive fluid from the conduit into the chamber and back into the motive fluid conduit, whereby the diverted portion of the motive fluid continuously introduces a portion of the lubricant into the motive fluid conduit to be carried along by the motive fluid.

4. An oiler comprising a vessel having a chamber adapted to contain a lubricant, a motive fluid conduit extending through the vessel and surrounded by the lubricant chamber, means to cause a portion of the air to pass through said air passage to said reservoir, means to cause the air to return to said passage from said reservoir, and means to prevent the discharge of oil from said reservoir except by the passage of said air.

5. An oiler comprising a vessel having a chamber adapted to contain a lubricant, internally projecting inlet and outlet tubes within the vessel, and an independent tube connecting the inlet and outlet tubes and adapted to admit the lubricant thereto.

6. An oiler comprising a vessel having a chamber adapted to contain a lubricant, internally projecting inlet and outlet tubes within the vessel, and an independent tube telescoping with the inlet and outlet tubes and adapted to admit the lubricant thereto.

7. An oiler comprising a vessel having a chamber adapted to contain a lubricant, internally projecting inlet and outlet tubes within the vessel, and an independent connecting tube inserted in the ends of the inlet and outlet tubes and adapted to admit the lubricant thereto.

8. An oiler comprising a vessel having a chamber adapted to contain a lubricant, internally projecting inlet and outlet tubes within the vessel and having their inner ends located contiguous to each other, and a perforated partition dividing the vessel into compartments which has a portion located between the contiguous ends of said inlet and outlet tubes.

9. An oiler comprising a vessel having a chamber adapted to contain a lubricant, internally projecting inlet and outlet tubes within the vessel, thimbles surrounding said tubes, and another tube connecting the inlet and outlet tubes.

10. An oiler for pneumatic tools comprising a vessel provided with internally projecting inlet and outlet tubes, and an adjustable tube connecting said inlet and outlet tubes and adapted to regulate the quantity of lubricant admitted thereto.

11. An automatic oiler for an air feed

pipe comprising a reservoir having its chamber provided with contracted bores for the attachment of adjacent ends of air-feed pipe sections, a tube leading through the chamber having its ends located in said contracted bores and ducts for opening communication from the chamber to the air feed pipe sections at the opposite ends of the said pipe.

12. An automatic oiler for an air feed pipe comprising a reservoir having its chamber provided with contracted bores for the attachment of the adjacent ends of air-feed pipe sections, a tube leading through the chamber having its ends located in said contracted bores and ducts in the exterior walls of the ends of the tube for opening communication from the chamber to the air-feed pipe sections for permitting the escape of oil at one end of the tube and the admission 20 of air at the other end of the tube.

13. An automatic oiler for an air feed pipe comprising a reservoir having its chamber provided with contracted bores for the attachment of the adjacent ends of the air-feed pipe sections, a tube leading through the chamber having its ends fitted to the said bores, there being ducts for opening com-

munication between the chamber and the air-feed-pipe sections at the opposite ends of the tube for permitting the escape of oil 30 in small quantities at the other end of the tube and an air-tight filling-cup for the said chamber.

14. An automatic oiler for an air-feed pipe comprising a reservoir having its chamber provided with contracted bores for the attachment of the adjacent ends of the air-feed-pipe sections, a tube leading through the chamber having its ends fitted to the bores and ducts at the opposite ends of the 40 tube for permitting the escape of oil from the chamber at the one or the other end of the tube according to the direction of flow of air through the air-feed pipe and the admission of air from the pipe to the chamber at the opposite end of the tube from the end where the oil is permitted to escape.

In testimony whereof I have hereunto signed my name in the presence of two subscribing witnesses,

JOHN C. BECKFIELD.

In the presence of—

CLARENCE A. WILLIAMS,
JOHN H. RONEY.
